CABINET FOR A RECHARGING BASE AND BATTERY OPERATED TOOTHBRUSH

LaVern G. Soper, Eau Claire, Wis., assignor to National
Presto Industries, Inc., Eau Claire, Wis., a corporation
of Wisconsin

Filed June 11, 1969, Ser. No. 17,628

Term of patent 14 years

Int. Cl. D4—02

U.S. Cl. D4—16

Fig. 1.

Fig. 2.

FIG. 1 is a perspective view of a cabinet for a battery operated toothbrush, showing my new design, with the cabinet closed;

FIG. 2 is a perspective view of the cabinet with the cabinet opened;

FIG. 3 is a back elevational view of the cabinet with the cabinet opened;

FIG. 4 is a front elevational view of the cabinet with the cabinet opened;

FIG. 5 is an elevational view of one side of the cabinet with the cabinet closed, the opposite side being a mirror image thereof;

FIG. 6 is a bottom plan view of the cabinet with the cabinet closed; and

FIG. 7 is a sectional view taken substantially along line 7-7 of FIG. 5 in the direction of the arrows, but turned 90°.

I claim:

The ornamental design for a cabinet for a recharging base and battery operated toothbrush, substantially as shown and described.
